UNITED STATES PATENT OFFICE

CHARLES H. OESTREICH, OF BROOKLYN, NEW YORK

DESIGN FOR TOILET-POWDER CONTAINER

Application filed November 4, 1930. Serial No. 37,529. Term of patent 7 years.

To all whom it may concern:

Be it known that I, CHARLES H. OESTREICH, a citizen of the United States, residing at Brooklyn, county of Kings, and State of New York, have invented a new, original, and ornamental Design for a Toilet-Powder Container, of which the following is a specification, reference being had to the accompanying drawing, forming a part thereof.

In the drawing

Fig. 1 is a perspective view of my new design.

Fig. 2 is a diagrammatic top plan view showing the periphery of the top and the periphery of the container itself.

I claim:

The ornamental design for a toilet powder container substantially as shown and described.

CHARLES H. OESTREICH.
